UNITED STATES PATENT OFFICE.

DANIEL RHODES, OF WASHINGTON, DISTRICT OF COLUMBIA.

DESIGN FOR A RECTAL DILATOR.

45,962.

Specification for Design.

Patented June 16, 1914.

Application filed October 11, 1913. Serial No. 794,745. Term of patent 7 years.

To all whom it may concern:

Be it known that I, DANIEL RHODES, a citizen of the United States, residing at Washington, District of Columbia, have invented a new, original, and ornamental Design for Rectal Dilators, of which the following is a specification.

Reference is had to the accompanying drawing, in which:

Figure 1 is a side elevation of a rectal dilator showing my new and ornamental design. Fig. 2 is a central longitudinal sec-

tional view of the same. Fig. 3 is a rear end view.

I claim:

The ornamental design for a rectal dilator substantially as shown.

In testimony, that I claim the foregoing as my own, I have hereto affixed my signature in the presence of two witnesses.

DANIEL RHODES.

Witnesses:

JOHN H. SIGGERS,
JOHN R. RAY.
